UNITED STATES PATENT OFFICE

1,923,037

ENGINE STARTER

Charles Marcus, New York, N. Y., assignor to
 Eclipse Machine Company, Elmira, N. Y., a
 Corporation of New York

Application July 6, 1925. Serial No. 41,859

29 Claims. (Cl. 123—185)

My invention relates to engine starting apparatus for starting internal combustion engines, more particularly airplane engines and the object thereof is to provide a simple, efficient and reliable apparatus for manual operation, preferably from opposite sides of the fuselage. My construction and arrangement of manually operated mechanism lends itself also to the combination therewith of an electric starting motor which may be applied thereto and operated either separately from or in conjunction with such mechanism, and it also lends itself to the combination therewith of a magneto in place of the motor so that when the engine is hand cranked the magneto may have a sufficient speed to give the desired spark for the engine ignition.

In the drawings, Fig. 1 is a sectional elevation of my apparatus on line 1—1 of Fig. 3; Fig. 2 an end elevation thereof looking at the engine engag- 20 gaging end thereof; Fig. 3 an elevation of the other end thereof showing a portion in section; Fig. 4 an elevation partly in section similar to Fig. 3 but illustrating the addition of a starting motor; Fig. 5 a detail section of the attachment 25 of the gear to the cranking shaft; Fig. 6 an elevation of the apparatus of Fig. 4 viewed from the opposite end; Fig. 7 a side elevation thereof; Fig. 8 an elevation similar to Fig. 4 but illustrating the application of a magneto in place of the 30 motor; and Fig. 9 an end elevation thereof.

Inasmuch as my invention concerns manually operated mechanism as the source of power or the addition thereto of a starting motor in a novel manner with respect to the modification 35 hereinafter described, the particular construction of the drive or transmission for automatic engagement with and disengagement from the member of the engine to be started is immaterial, and therefore, any suitable drive or transmission 40 of this character may be employed. However, I prefer to employ the particular drive or transmission illustrated in the drawings, particularly in Fig. 1 thereof, the same being the subject matter of a copending application.

First describing the automatic drive or transmission illustrated in Fig. 1, the same is located within a main casing 1 within which is preferably provided a bushing 2. Within this bushing rotates a barrel 3 and a shell 4 concentrically arranged therewithin and providing a considerable annular space between them to receive a yieldable driving connection which is here in the form of a friction clutch 5. The sets of clutch plates are splined respectively to the interior of the 55 barrel and the exterior of the shell. The proper

pressure is provided for the friction plates by means of a series of springs 6 which are located in such annular space between the barrel and shaft and such pressure is regulated by the adjustable nut 7. Within the shell 4, there is mounted a screw shaft 8 having long lead threads 9 which are threaded to the internally threaded or nut portion 10 of the shell. This shaft is provided at its outer end with a driving member which is here in the form of a splined member or part 11 adapted when moved longitudinally to engage a rotatable member of the engine to be started, which latter member is here the engine crank shaft 12 provided with internal splines. This engaging movement may be limited by any 70 suitable means, as by the provision of a stop nut 13 adapted to engage the end face of the threaded portion 10 of the shell when the splined part 11 has become fully meshed with the crank- 75 shaft 12.

When the barrel is rotated in the manner hereinafter explained, such rotation is imparted to the shell 4 through the friction clutch with the result that by reason of the threaded connection between such shell and shaft, the latter is moved outwardly to the left in Fig. 1 and the splined portion thereof is engaged with the engine member and the engine is thereupon cranked. When the engine starts on its own power the excess speed of rotation of the engine member 12 will cause shaft 85 8 to be screwed backwardly, thereby causing the splined portion to be automatically demeshed and the shaft to be restored to normal position as shown in Fig. 1, at which time the abutment nut 13 is in contact with the bushing or hub 14 of the 90 main drive wheel 15 of the apparatus.

Describing the means for actuating the drive or transmission, the main drive wheel 15 is in the form of a worm wheel having the peripheral worm portion 16. The main casing 1 is extended 95 to form an extension or supplementary casing 17 within which is journaled the hand crank shaft 18. This shaft is provided at its middle portion with worm 19 meshing with the worm gear 15 and its bearings 20 and 21 are located immediately adjacent the worm, and moreover, such shaft extends beyond such bearings and extraneous of the casing 17, preferably at both ends thereof, as shown in Fig. 3. This hand crank shaft at its opposite ends extraneous of the casing is provided with crank engaging means such as pins 22 and 23 adapted to be engaged by the usual hand crank for an internal combustion engine.

This crank shaft itself may extend through the 110

opposite sides of the fuselage of the airplane when the apparatus is used in connection with an airplane engine or separate extensions may be provided which are thrust through openings in the 5 sides of the fuselage and the hand crank thereupon applied.

Describing the operation of the apparatus, rotation of the shaft 18 will rotate the worm 19 and rotate the worm wheel 15 through a considerable 10 reduction. Rotation of this wheel will rotate the barrel 3 and operate the drive or transmission in the manner hereinbefore explained.

My construction of manually operated mechanism lends itself readily to the application of a 15 starting motor in the event that a prime mover is desired in addition to the manual power. To such end, the starting motor is attached to the supplementary casing 17 which has a suitable pad portion to receive it and gearing is provided between 20 the starting motor and the hand crank shaft 18.

Describing the particular embodiment of the combined apparatus shown in Figs. 4, 5, 6 and 7, a starting motor 24 is suitably mounted and secured 25 to the casing 17 and its armature shaft is provided with a pinion 25 which meshes with a gear 26 operatively connected with the hand crank shaft 27 which now also becomes a power shaft. The shaft shown in Fig. 4 is somewhat longer than 30 the shaft 18 of Fig. 3 in order to make provision for hand cranking at the left hand end thereof, but as shown in the modification, Fig. 5, identically the same shaft is used as in Fig. 3. The pinion 25 and gear 26 are suitably housed by means of a 35 casing 28 forming a part of the end plate or head of the electric motor. The main casing is closed at its end adjacent the wheel 15 by means of a removable plate 29. As shown the gear 26 is operatively connected to shaft 27 by pin and slot connection as by means of the transverse cranking pin 30 engaging slots 31 in the bore of the hub of such gear.

The motor assembly contains a complete gear reduction within itself, the driven gear being entirely restrained in its casing 28 by the two external annular bearings 28a. With the use of the pin and slot driving connection having the considerable clearance between them, this makes for a simple application of the motor assembly to the 50 starter casing without accuracy and with ease.

The motor 24 is detachably secured to the casing 17 and preferably indirectly thereto through the medium of a platform 32 which is secured to the pad 33 of the casing by means of screws 34. This 55 platform is employed in case of installation on an airplane wherein the longitudinal space between the face of the engine crank case to which the starter apparatus is mounted and the fire wall is very limited so that in mounting the apparatus 60 upon the crank case, it is impossible to make the pad sufficiently wide of itself to accommodate the base of the motor. For this reason, the platform is used which is applied and secured to the casing 17 after the assembly of the apparatus including 65 the casing to the engine.

The platform is channeled to an accurate width so as to receive the base of the motor, the same being located endwise by the two pins 35 near the edge of the platform. Two rods 36 pass through 70 the ears 37 of the platform and to these rods are attached the hooks 38 secured to the ends of a strap 39 which passes over the body of the motor and clamps the same firmly to the platform. The strap is tightened by adjusting the cap screw 40 75 which is locked in place by the lock nut 41.

Describing the operation of the apparatus with the motor drive, when the motor is energized and the armature shaft is rotated, the cranking shaft 27 is likewise rotated with the results hereinbefore described. If desired or when necessary in case 80 of a low storage battery, the power of the motor may be supplemented by hand cranking. This construction enables the same starter unit to be employed for either power or hand cranking. Where a battery is carried on an airplane, such as the case of the larger airplanes used for observation or bombing, the motor may be employed, but where a battery is not carried as in the case of small airplanes, such as pursuit airplanes, the 85 motor and its connections may be removed, the remainder of the apparatus being the hand cranking unit.

As shown in Fig. 5, identically the same cranking shaft may be employed as in the structure of Fig. 3 in which event the structure is somewhat modified as compared with Fig. 4, such modification consisting in extending the hub 42 and providing a cranking tube 43 which is pinned to such hub at one end and to whose other end the ordinary hand crank is applied. In this modification, the crank engaging pin 22 is utilized as the driving connection between the shaft 27 and the gear wheel 26.

My apparatus also lends itself to the installation, in combination with the starter mechanism, 105 of a magneto which may be applied thereto upon the platform and pad of the casing 17, in the same manner as the motor. The purpose of such magneto is to furnish sufficient sparking for the ignition during the comparatively slow cranking 110 rotation of an engine that is equipped with magneto ignition which functions properly only at the normal or higher speed. As shown in Figs. 8 and 9, the magneto 44 is secured to the platform by a similar strap 39 as in the case of the motor 115 and the same is driven from the cranking shaft 27 through compound gearing which comprises a main gear 45 pinned to the cranking shaft 27 by the crank pin 22, a pinion 46 mounted to rotate freely on a stud 47 mounted in a bracket 48, a gear 120 wheel 49 rigidly secured or integral with the pinion 46, and a pinion 50 secured to the magneto shaft 51. These gears and pinion constitute the driving train between the cranking shaft 27 and the magneto shaft and serve to rotate such magneto at such high speed as to give the sufficient spark for the engine ignition during the cranking 125 operation and until the regular magneto of the engine is rotated thereby at sufficiently high speed to function normally to furnish the ignition. The gear 45 has an extended hub 52 which receives a cranking tube 53 pinned thereto by a pin 54. The other end of this tube has the usual spiral slots to receive the usual hand crank, wherefore in this construction, as well as that of Figs. 4 130 and 5 the apparatus may be cranked at either end of the shaft 27 notwithstanding the presence of the train of gears used for either the motor or the magneto, whichever is used.

When the shaft 27 is rotated by the hand 140 crank, the drive or transmission is operated in the manner already described and the magneto 44 is simultaneously operated at comparatively high speed. In practice, this booster magneto is operated at a speed of ten times that of the hand 145 crank which is sufficiently high to furnish the proper spark for the engine ignition during cranking.

The machines herein shown and described, to-wit, the electric motor of Fig. 4 and the electric 150

generator or magneto of Figs. 8 and 9, are both dynamo electric machines which are operatively connected with the cranking shaft, the motor driving such shaft through said connections and the generator or magneto being driven by such shaft through said connections. Generically speaking, both of these machines are dynamo electric machines and such term is used in the claims to cover either machine.

10 I claim:

1. An engine starter including a driving member adapted to engage and crank a member of the engine to be started, a rotatable member for actuating such driving member, a friction clutch between said driving member and rotatable member and a manually operated shaft operatively connected with such rotatable member and constructed and arranged to be operated at either end.

20 2. An engine starter including a driving member adapted to engage and crank a member of the engine to be started, a rotatable member for actuating such driving member, a friction clutch between said driving member and rotatable member and a manually operated shaft operatively connected with such rotatable member and having clutch means at both of its ends.

30 3. An engine starter including a driving member adapted to engage and crank a member of the engine to be started, a rotatable member for actuating such driving member, a friction clutch between said driving member and rotatable member a casing, and a manually operated shaft journalled in such casing and having its ends extending extraneous of the casing and provided with clutch means for operation from either end.

40 4. An engine starter including a driving member adapted to engage and crank a member of the engine to be started, a worm wheel operatively connected with the driving member by connections including an adjustable friction clutch, and a worm engaging such wheel and having a shaft extending on both sides of the worm, both ends of the shaft being provided with clutch means for operation from either end.

50 5. An engine starter including a driving member adapted to engage and crank a member of the engine to be started, a worm wheel operatively connected with the driving member by connections including an adjustable friction clutch, a casing for such wheel, such casing having an extension, and a worm located within such extension and having a shaft extending on both sides of the worm and journalled in the casing extension, said shaft extending at both ends extraneous of said extension and being provided with clutch means for operation from either end.

60 6. An engine starter including a casing, a barrel rotatable therewithin, a substantially cylindrical shell concentric of and drivingly connected with the barrel by connections including an adjustable friction clutch, a driving member located within and rotatable by the shell and mounted for longitudinal movement to engage and crank a member of the engine to be started, a worm wheel secured to the barrel, and manually operated means for actuating such wheel.

70 7. An engine starter including a casing, a barrel rotatable therewithin, a substantially cylindrical shell concentric of and drivingly connected with the barrel by connections including an adjustable friction clutch, a driving member located within and rotatable by the shell and mounted for longitudinal movement to engage and crank a member of the engine to be started, a worm

wheel secured to the barrel, and a manually operated worm for actuating such wheel.

8. An engine starter including a casing, a barrel rotatable therewithin, a substantially cylindrical shell concentric of and drivingly connected with the barrel by connections including an adjustable friction clutch, a driving member located within the shell and mounted for longitudinal movement to engage and crank a member of the engine to be started, a worm wheel secured to the barrel, and means whereby such wheel may be operated from either side of its axis.

9. An engine starter including a casing, a barrel rotatable therewithin, a substantially cylindrical shell concentric of and drivingly connected with the barrel, a driving member located within and rotatable by the shell and mounted for longitudinal movement to engage and crank a member of the engine to be started, means coacting with a driving member for controlling the longitudinal movements of the driving member, a worm wheel secured to the barrel, and a worm engaging such wheel and having a shaft extending on both sides of the worm, the operating connections between the worm wheel and said driving member including an adjustable friction clutch.

10. An engine starter including a casing, a barrel rotatable therewithin, a substantially cylindrical shell concentric of and drivingly connected with the barrel, a driving member located within the shell and mounted for longitudinal movement to engage and crank a member of the engine to be started, means coacting with the driving member and shell for controlling the longitudinal movements of the driving member, a worm wheel secured to the barrel, and a worm engaging such wheel and having a shaft extending on both sides of the worm, both ends of the shaft being provided with clutch means for manual operation from either end, said casing having an extension which encloses the worm wheel and in which the worm shaft is journalled.

11. An engine starter including a driving member adapted to engage and crank a member of the engine to be started, means including a rotatable member for actuating such driving member, a casing, means for automatically moving the driving member into engagement with the engine member, a manually operated shaft journalled in such casing and having its ends extending extraneous of the casing and provided with clutch means for manual operation from either end, and a motor mounted upon such casing and drivingly connected with said shaft.

12. An engine starter including a driving member adapted to engage and crank a member of the engine to be started, a rotatable member for actuating such driving member, a casing, and a manually operated shaft journalled in such casing and having its ends extending extraneous of the casing and provided with clutch means for manual operation from either end, a motor mounted upon such casing, a gear secured to one end of the shaft on the inner side of its clutch means, and a pinion meshing with the gear and driven by the motor.

13. An engine starter including a driving member adapted to engage and crank a member of the engine to be started, a rotatable member for actuating such driving member, a cranking shaft operatively connected with such rotatable member, a casing in which such cranking shaft is mounted and which has a pad, a detachable platform connected with said pad, an electric

- motor detachably connected with such platform, and driving connections between the armature shaft of the motor and said cranking shaft.
14. An engine starter including a driving member adapted to engage and crank a member of the engine to be started, a rotatable member for actuating such driving member, a cranking shaft operatively connected with such rotatable member, a casing in which the cranking shaft is mounted, an electric motor mounted on the casing, and a train of gears between the cranking shaft and the armature shaft of the motor carried by the motor casing and including a gear having a hub with pin and slot connection with the cranking shaft for endwise removal therefrom.
15. An engine starter including a driving member adapted to engage and crank a member of the engine to be started, a rotatable member for actuating such driving member, a cranking shaft operatively connected with such rotatable member, and having near its end a cranking pin, a casing in which the cranking shaft is mounted, an electric motor detachably mounted on the casing, and a train of gears between the cranking shaft and the armature shaft of the motor and carried by the motor for detachment therewith, said train including a gear having a hub with opposite internal slots adapted to receive the projecting ends of such pin.
16. An engine starter including a driving member adapted to engage and crank a member of the engine to be started, a rotatable member for actuating such driving member, a cranking shaft operatively connected with such rotatable member, a casing in which such shaft is mounted and which is provided with a pad, a platform detachably connected with such pad, a dynamo electric machine secured to said platform, and driving connections between said cranking shaft and the dynamo electric machine.
17. An engine starter including a driving member adapted to engage and crank a member of the engine to be started, a rotatable member for actuating such driving member, adjustable friction clutch means for drivably connecting said driving member and rotatable member, a manually operable cranking shaft operatively connected at its central portion with such rotatable member and constructed and arranged to be operated at either end.
18. An engine starter including a driving member adapted to engage and crank a member of the engine to be started, a rotatable member for actuating such driving member, friction clutch means for drivably connecting said driving member and rotatable member, a manually operable cranking shaft operatively connected with such rotatable member and constructed and arranged to be manually operated at either end.
19. An engine starter including a driving member adapted to engage and crank a member of the engine to be started, a rotatable member for actuating such driving member, a casing which encloses such driving member and rotatable member and in which they are mounted, a worm wheel connected with the rotatable member and contained within the casing the operating connections between said worm wheel and said driving member including an adjustable friction clutch, a driving shaft also mounted in such casing and having intermediate its length a worm cooperating with said wheel, said shaft extending extraneous of the casing to receive application of torque.
20. An engine starter including a driving member adapted to engage and crank a member of the engine to be started, a rotatable member for actuating such driving member, a casing which encloses such driving member and rotatable member and in which they are mounted, a driving shaft also mounted in such casing and operatively connected intermediate its ends with said rotatable member, said shaft extending extraneous of the casing and having an exposed non-circular formation to receive a hand crank for application of torque, and backfire protective means interposed between said rotatable and driving members.
21. In combination, a driven member adapted to engage a member of an engine to be started, a driving barrel, friction clutch means in the barrel for drivably connecting said barrel and driven member, a manually operable shaft extending transversely of the longitudinal axis of the barrel, means drivably connecting said shaft and barrel, and an electrical machine drivably connected to said shaft.
22. In combination, a casing, a barrel rotatably mounted in said casing, a driven member adapted to engage a member of an engine to be started, a friction clutch for drivably connecting said barrel and driven member, a manually operable shaft, worm gearing for drivably connecting said shaft to said barrel, an electrical machine mounted on said casing, and means for drivably connecting said electrical machine to said shaft.
23. An engine starter including a driving member adapted to engage and crank a member of the engine to be started, a rotatable member for actuating said driving member, yielding means for drivably connecting the driving member and rotatable member, a manually operable cranking shaft operatively connected with said rotatable member, and gear means connected with said shaft for readily connecting a generator or a motor thereto, whereby the motor may drive the cranking shaft or the cranking shaft may be used to actuate the generator.
24. In an engine starter, in combination with a longitudinally grooved member constituting a permanently connected part of the engine proper, a correspondingly grooved driving member engageable with said engine member, power actuating means therefor, an adjustable multi-disc friction clutch mechanism interposed between said power means and said grooved members, and means including a worm and gear reduction unit for drivably connecting said power means with said friction clutch mechanism.
25. In an engine starter, in combination with a hollow rotatable member constituting a permanently connected part of the engine proper, a driving member engageable with the internal surface of said hollow rotatable member, power actuating means therefor, an adjustable multi-disc friction clutch mechanism interposed between said power means and said members, and means including a worm and gear reduction unit for drivably connecting said power means with said friction clutch mechanism.
26. In an engine starter, in combination with a longitudinally grooved member constituting a permanently connected part of the engine proper, a correspondingly grooved driving member engageable with said engine member, an adjustable barrel member disposed in coaxial alignment with said engine member, a friction clutch mechanism constituting a driving connection of limited torque capacity interposed between said bar-

rel member and said engine-engaging member, and alternative power and manually operated means operatively connected with said barrel member.

- 5 27. In an engine starter, in combination with a hollow rotatable member constituting a permanently connected part of the engine proper, a driving member engageable with the internal surface of said hollow rotatable member, a barrel member disposed in coaxial alignment with said engine member, a friction clutch mechanism constituting a driving connection of limited torque capacity interposed between said barrel member and said engine-engaging member, and alternative power and manually operated means operatively connected with said barrel member.
- 10 28. In an engine starter, in combination with a longitudinally grooved member constituting a permanently connected part of the engine proper, a correspondingly grooved driving member engageable with said engine member, a barrel member disposed in coaxial alignment with said engine member, a friction clutch mechanism constituting a driving connection of limited torque capacity interposed between said barrel member and said engine-engaging member, and alternative power and manually operated means operatively connected with said barrel member.
- 15 29. In an engine starter, in combination with a longitudinally grooved member constituting a permanently connected part of the engine proper, a correspondingly grooved driving member engageable with said engine member, a barrel member disposed in coaxial alignment with said engine member, a friction clutch mechanism constituting a driving connection of limited torque capacity interposed between said barrel member and said engine-engaging member, and a gear reduction mechanism having at least a portion thereof common to both said power and manually operated means.
